CLAIM

The ornamental design for a depilator, as shown and described.

DESCRIPTION

FIG. 1 is a front elevational view of a depilator showing my new design;

FIG. 2 is a top plan view thereof;

FIG. 3 is a right side elevational view thereof, the side opposite being a mirror image of the side shown;

FIG. 4 is a bottom plan view thereof; and

FIG. 5 is a rear view thereof.

FIG. 1

FIG. 5

FIG. 2

FIG. 3

FIG. 4
